GOLF BAG

Filed June 25, 1928

Inventor:
Benedict F. Shanahan,
By Dampf, Lee, Chaffin & Miller,
Attys.

UNITED STATES PATENT OFFICE.

BENEDICT F. SHANAHAN, OF CHICAGO, ILLINOIS.

GOLF BAG.

Application filed June 25, 1928. Serial No. 287,954.

This invention relates to improvements in golf bags, and more especially to means for supporting a golf bag in an upright position.

In that form of device embodying the features of my invention shown in the accompanying drawings, Fig. 1 is a view in side elevation showing the legs of the supporting mechanism extended; Fig. 2 is a view taken as indicated by the line 2 of Fig. 1; Fig. 3 is a view of the lower end of the bag showing the legs of the supporting mechanism drawn in, and Fig. 4 is a partial bottom plan view of the apparatus shown in Fig. 2.

As shown in the drawings, 10 indicates a golf bag, which may be of the ordinary form, having at the bottom end the metal supporting ring 11.

The supporting mechanism, as here shown, is detachable and comprises a metal band 12 adapted to be fastened to the lower end of the bag and held in position by drawing the ends together by means of bolts 13.

The band 12 is provided with five slots 14 adapted to accommodate the radial legs 15 which are here shown made of a curved piece of metal with widened ends 15^a.

The inner ends of the legs 15 are pivotally attached at 15^b to a leg carrying-member 16 which is adapted to move upwardly and downwardly with respect to the bottom 17 of the golf bag.

The ring 12 also carries the cross-bars 18, and the upper side of the leg-carrying member 16 is provided with clamps 19 adapted to snap over the bars 18 when the member 16 is moved upwardly.

When the leg-carrying member 16 is moved upwardly, as shown in Fig. 2, the legs 15 are extended and the clamps 19 engage the rods 18. The outer ends of the legs thus serve to engage the turf and support the bag in upright position.

When the bag is lifted, the member 16 may be pulled downwardly, as shown in Fig. 3, to release the clamps 19 from the bars 18 to cause the legs 15 to be pulled inwardly, as shown in this figure. Releasing of the clamps may be effected by kicking the legs 15 inwardly or by exerting unusual force upwardly against the end of one, thus causing the clamp 19 to be released.

The member 16 may be pushed upwardly by pressing the bag down against the ground or turf, thus causing the member 16 to move upwardly until the clamps 19 engage the rods 18. 55

While I have shown and described certain embodiments of my invention, it is to be understood that it is capable of many modifications. Changes, therefore in the construction and arrangement may be made without departing from the spirit and scope of the invention as disclosed in the appended claims, in which it is my intention to claim all novelty inherent in my invention as broadly as possible in view of the prior art. 65

What I claim as new, and desire to secure by Letters Patent, is:

1. In combination with a golf bag; a vertically movable leg-carrying member below the bottom of the bag and adapted to rest on the ground and be moved upwardly toward the bottom of the bag when the bag is placed on the ground; and a plurality of radial legs pivotally attached to said leg-carrying member and extending through bearings adjacent the lower edge of the bag, said legs adapted to be projected outwardly through said bearings to cause their outer ends to contact with the ground when the leg-carrying member is moved upwardly, and be drawn inwardly 70 through said bearings when the leg carrying member is moved downwardly. 75

2. A device as claimed in claim 1, in which the legs have stops on their ends to limit their inward movement through the bearings. 80

3. A device as claimed in claim 1, in which the legs are curved.

4. In combination with a golf bag; a depending circular supporting member at the bottom thereof with openings therein; a vertically movable leg-carrying member below the bottom of the bag and adapted to rest on the ground and be moved upwardly inside of said supporting member when the bag is placed on the ground; and a plurality of radial legs pivotally attached to said leg-carrying member and extending through the openings in the circular supporting member, said legs adapted to be projected outwardly 90 through said openings to cause their outer ends to contact with the ground when the leg-carrying member is moved upwardly, and be 95

drawn inwardly through said openings when the leg-carrying member is moved downwardly.

5. A device as claimed in claim 4, in which the legs have stop members on their ends to limit their inward movement through the openings.

6. A device as claimed in claim 1 with

means for yieldingly holding the leg-carrying member in its upper position. 10

7. A device as claimed in claim 4 with means for yieldingly holding the leg-carrying member in its upper position.

In witness whereof, I have hereunto set my hand this 22nd day of June, 1928.

BENEDICT F. SHANAHAN.
